US00D880464S

(12) **United States Design Patent** (10) Patent No.: **US D880,464 S**
(45) Date of Patent: ** Apr. 7, 2020

(54) **ELECTRONIC DEVICE**

(71) Applicant: **Samsung Electronics Co., Ltd.**, Suwon-si (KR)

(72) Inventors: **Han-Gil Song**, Seoul (KR); **Jung-Hyuck Im**, Yongin-si (KR); **Min-Hyouk Lee**, Seoul (KR)

(73) Assignee: **Samsung Electronics Co., Ltd.**, Suwon-si (KR)

(**) Term: **15 Years**

(21) Appl. No.: **29/631,053**

(22) Filed: **Dec. 27, 2017**

Related U.S. Application Data

(63) Continuation of application No. 29/515,011, filed on Jan. 20, 2015, now Pat. No. Des. 808,916, which is a continuation of application No. 29/428,443, filed on Jul. 31, 2012, now Pat. No. Des. 723,491, which is a continuation-in-part of application No. 29/425,168, filed on Jun. 20, 2012, now Pat. No. Des. 695,253.

(57) **CLAIM**

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of the electronic device that form no part of the claimed design.

1 Claim, 8 Drawing Sheets
